UNITED STATES PATENT OFFICE.

NATHAN M. CROSBY, OF NEW YORK, N. Y., ASSIGNOR TO THE WEBSTER PIANO COMPANY, OF BROOKLYN, NEW YORK, A CORPORATION OF NEW YORK.

DESIGN FOR A CASE FOR PIANOS AND PLAYER-PIANOS.

43,841.

Specification for Design.

Patented Apr. 15, 1913.

Application filed January 27, 1913. Serial No. 744,584. Term of patent 7 years.

To all whom it may concern:

Be it known that I, NATHAN M. CROSBY, a citizen of the United States of America, and a resident of the borough of Brooklyn, in the city and State of New York, have invented a new, original, and ornamental Design for a Case for Pianos and Player-Pianos, of which the following is a specification, reference being had to the accompanying drawing, forming part thereof.

The figure is a perspective view of an upright piano showing my said design.

I claim:

The ornamental design for a case for pianos and player pianos, substantially as shown.

NATHAN M. CROSBY.

Witnesses:

A. H. TAYLOR,
A. J. POWELL.
